UNITED STATES PATENT OFFICE.

HENRY C. MANCHESTER AND SAMUEL S. RIEGEL, OF SCRANTON, PENNSYLVANIA.

BY-PASS VALVE FOR LOCOMOTIVE-ENGINES.

1,089,570.

Specification of Letters Patent. Patented Mar. 10, 1914.

Application filed August 21, 1913. Serial No. 785,889.

To all whom it may concern:

Be it known that we, HENRY C. MANCHESTER and SAMUEL S. RIEGEL, both of Scranton, in the county of Lackawanna and State of Pennsylvania, have jointly invented a certain new and useful Improvement in By-Pass Valves for Locomotive-Engines, of which improvement the following is a specification.

This invention relates to locomotive engines, and has for its principal object to provide an improved valve mechanism for automatically opening communication through a by-pass between the opposite ends of the engine cylinder when the locomotive is drifting, or running with the throttle closed, thereby permitting free passage of the contents of the cylinder from one end to the other, and maintaining the piston substantially balanced as to pressure upon its opposite sides in all positions.

Another feature of our improvement consists in means for admitting a limited quantity of steam at the same time that the by-pass is open, and thereby prevent the formation of a vacuum in the cylinder, assist in the lubrication, eliminate the carbonization of oil and prevent the chilling of the cylinder walls by the indraft of cold air.

Our improvement is particularly useful for engines operating with superheated steam, in which the parts are maintained at high temperatures, but it is also applicable in connection with engines using saturated steam.

In the practice of our invention we preferably employ a valve of the differential hollow piston type, subject to the opposing pressures of the engine valve steam chest, and the live steam from the boiler, whereby, when the throttle is open, the high pressure from the steam chest operates to hold the by-pass closed, but when the throttle is closed and the pressure from the steam chest falls, the opposing boiler pressure operates to open the by-pass and to admit a limited quantity of live steam into the cylinders.

In the accompanying drawings: Figure 1 is a vertical section through a locomotive engine cylinder and steam chest, showing in section one form of our improved valve mechanism applied thereto; Fig. 2, a central section, on a larger scale, of one of the improved valve mechanisms; Fig. 3, a transverse section taken on the line 3-3 of Fig. 2; Fig. 4, an end elevation of the valve cas-

ing; Fig. 5, a side elevation of the engine cylinder and valve mechanism, showing the pipe connections; and Fig. 6, a sectional detail view showing a slightly modified form of valve.

According to the construction shown in the drawings, our improvement is illustrated in connection with a locomotive engine having a cylinder, 7, a steam chest, 8, adapted for a steam distribution valve of the piston type, and induction and eduction ports, 9, leading from the steam chest to the opposite ends of the cylinder. The by-pass, 21, establishes communication between the opposite induction ports and, when open, affords a free passage from one end of the cylinder to the other. The by-pass valves, 10, two being shown in this instance, are mounted in chambers, 11, each communicating with an induction and eduction port, 9, leading to the cylinder, and each valve may be in the form of a differential hollow piston closed at the valve end and having an intermediate piston portion, 10^a, fitting the bore of the middle part of the valve casing, 12, and a larger piston portion, 10^b, fitting an enlarged outer chamber, 12^a, which is closed by the cap, 13. For the purpose of assisting in supporting and guiding the valve in its movement, the cap is provided with a central plunger-like projection, 13^a, extending within the hollow piston valve. This makes a very light construction, and the chamber, 14, thus formed within the piston valve, serves as a dash pot for cushioning the action of the valve. A small port, 15, may be drilled through the wall of the valve from the valve chamber into the dash pot, 14, for slowly relieving the pressure therein. An adjustable screw stem, 16, may be mounted in the cap, 13, and extend through the same to a position to limit the opening movement of the valve, or it may be screwed down to hold the valve closed upon its seat whenever desired.

The chamber, 12^a, at the outer end of the large piston, 10^b, is in communication with the steam chest, 8, of the distribution valve by means of pipe, 18, while live steam pressure from the boiler is admitted through pipe, 19, to the annular chamber, 17, between the differential heads, 10^a and 10^b, of the hollow piston valve. Grooves, 20, are formed longitudinally in the bore of the valve casing to serve as ports for opening communication around the piston head, 10^a.

when the valve moves to its open position, and thereby admit a limited quantity of steam into the valve chamber, by-pass and engine cylinder. Packing rings may be 5 mounted on the differential piston portions for preventing leakage around the same.

When the locomotive is running with the throttle open, the steam admitted through the throttle to the steam chest also passes 10 through pipe, 18, into chamber, 12^a, and acting on the large annular area of piston head, 10^a, holds the valve, 10, upon its seat with the by-pass closed. The live steam pressure from the boiler admitted through pipe, 19, 15 to the annular chamber, 17, acts upon the differential piston in the opposite direction to the pressure in chamber, 12^a, but over a smaller effective area, and therefore is insufficient to move the piston to open the 20 valve. When the throttle is closed and the locomotive continues running, or drifting, the pressure in the steam chest, and consequently in chamber, 12^a, falls rapidly, and as soon as the opposing boiler pressure in 25 chamber, 17, acting on the smaller effective area of piston, 10^a, overcomes the diminishing pressure in chamber, 12^a, the differential piston moves the valve away from its seat and opens the by-pass between the opposite 30 ends of the cylinder. As the piston continues to move outward, the head, 10^a, reaches a position in which the grooves, 20, open communication around said piston head, and thereby admit a limited quantity 35 of steam into the valve chamber, by-pass and through the ports into both ends of the cylinder. The engine piston is thus balanced as to fluid pressure upon its opposite sides, and the contents of the cylinder pass freely from 40 one end to the other, through the by-pass, as the piston reciprocates. The small amount of live steam admitted serves to prevent a vacuum being formed in the cylinder by the pumping action of the piston, and maintains 45 the temperature of the cylinder walls, which is very important, particularly where superheated steam is employed. It also serves to lubricate the cylinder, and prevents the carbonization of the oil. When the throttle is 50 again opened, the steam pressure from the steam chest admitted to chamber, 12^a, acts upon the larger area of the piston head, 10^a, and, overcoming the boiler pressure in chamber, 17, moves the piston and valve to cut 55 off the grooves, 20, and close the by-pass. The differential piston is supported and guided in its movement upon the long cylindrical bearing of the projection, 13^a, within the hollow piston, and the chamber, 14, 60 serves as a dash pot to cushion the action of the valve in opening and closing. By means of this construction, the valve may be made very light and durable, and injury to the parts by excessive hammering of the valve 65 will be avoided.

While the valve is shown as formed integral with the differential piston in Figs. 1 and 2, it will be obvious that it may be made structurally separate therefrom, and connected to said piston in any suitable or 70 preferred manner. As shown in Fig. 6, the valve, 10^a, is formed separate and connected to the differential piston by a stem, 10^a. It is also provided with a curved joint connection, 10^a, by means of which the valve is adjustably mounted so as to compensate for any slight difference in the alinement of the valve and its seat, and insure the positive closure of the valve.

We claim as our invention and desire to 80 secure by Letters Patent:

1. In a locomotive engine, the combination with the cylinder, steam chest, and a by-pass connecting the opposite ends of the cylinder, of a valve for controlling said by-pass, and means governed by the opposing pressures of the steam chest and the boiler for operating said valve.

2. In a locomotive engine, the combination with the cylinder, steam chest, and a by-pass connecting the opposite ends of the cylinder, of a valve for controlling said by-pass, and a movable abutment subject in one direction to pressure from the steam chest tending to close said valve, and in the opposite direction to pressure from the boiler tending to open said valve.

3. In a locomotive engine, the combination with the cylinder, steam chest, and a by-pass connecting the opposite ends of the cylinder, of a valve for controlling said by-pass, a movable abutment subject to opposing pressures from the steam chest and from the boiler for operating said valve, and means also controlled by said abutment for admitting a limited quantity of steam into the cylinder when said valve is open.

4. In a locomotive engine, the combination with the steam chest, the cylinder having induction ports at its opposite ends, and a by-pass connecting said ports, of valves for controlling communication between said ports and by-pass, and differential piston means subject to the steam chest pressure on one side and to the boiler pressure on the other side for operating said valves.

5. In a locomotive engine, the combination with the steam chest, cylinder, and by-pass, of a by-pass valve mechanism comprising a casing containing a chamber communicating with said by-pass, and a differential piston valve mounted in said chamber and operated by the opposing pressures from the steam chest and from the boiler, said piston containing a dash pot chamber for cushioning the movement of said valve.

6. In a locomotive engine, the combination with the steam chest, cylinder, and by-pass, of a by-pass valve mechanism comprising a casing containing a chamber communi-

cating with said by-pass, and a differential piston valve mounted in said chamber and operated by the opposing pressures from the steam chest and from the boiler to control 5 said by-pass and the admission of a limited quantity of steam into the cylinder.

7. In a locomotive engine, the combination with the steam chest, cylinder, and by-pass, of a by-pass valve mechanism comprising a casing containing a chamber communicating with said by-pass, a differential piston valve mounted in said chamber, having a hollow body and subject in one direction to pressure from the steam chest, and a 10 fixed guide extending within the hollow body of the piston valve and forming a support therefor and a dash pot closure therein.

8. In a locomotive engine, the combination with the steam chest, and cylinder having a by-pass connecting the opposite ends thereof, of a valve controlling said by-pass and having a differential piston subject to the opposing pressures of the steam chest and the boiler, and a casing having passages 20 controlled by the movement of said differ-

ential piston for admitting a limited quantity of live steam to the cylinder.

9. In a locomotive engine, the combination with the steam chest, and cylinder having a by-pass connecting the opposite ends 30 thereof, of a valve controlling said by-pass, a piston movable in a chamber in line with the valve seat for operating said valve, and an adjustable connection between the piston and said valve to compensate for slight differences in alinement.

10. In a locomotive engine, the combination with the cylinder, steam chest, and a by-pass connecting the opposite ends of said cylinder, of a hollow piston valve subject to 40 fluid pressure for controlling said by-pass, a guide projecting within the hollow piston, and an adjustable stem extending through said guide for limiting the travel of said valve.
